[57] **CLAIM**

The ornamental design for a multi-purpose rack for chemical reagent vessels, as shown and described.

DESCRIPTION

FIG. 1 is a perspective view of a multi-purpose rack for chemical reagent vessels showing my new design; FIG. 2 is a top plan view thereof;

FIG. 3 is a bottom plan view thereof;

FIG. 4 is a side elevational view, with the opposite side appearing as a mirror image thereof; and,

FIG. 5 is an end elevational view thereof, with the opposite end appearing the same.

FIG. 2

FIG. 3

FIG. 4

FIG. 5
